PROCESS FOR REFINING HYDROCARBON OILS

Johannes Arnoldus Buchel and Reyerus Nicolaas Jan Saal, Amsterdam, Netherlands, assignors, by mesne assignments, to Shell Development Company, San Francisco, Calif., a corporation of Delaware

Application July 18, 1929, Serial No. 379,310, and in the Netherlands July 23, 1928

29 Claims. (Cl. 196—37)

Our invention relates to a process for refining hydrocarbons by extracting with liquid sulphur dioxide. More particularly, the invention relates to a method of improving the extraction by the use of an auxiliary substance in connection with the liquid sulphur dioxide.

It is known that hydrocarbons, for instance fractions obtained in the distillation of petroleum, can be refined with liquid sulphur dioxide. This process, called edeleanuization after the name of the inventor, has as its main object the removal of the aromatic compounds. It consists in principle in bringing the material to be refined in contact with liquid SO_2 at temperatures of about -10 degrees C., which causes two layers to form. The upper layer, the raffinate layer, contains the more or less aromatic-free material, whilst the lower layer, the extract layer, consists of liquid SO_2 in which the aromatics are mainly dissolved.

In the attached drawing (Fig. 1) a graphic representation is given of the proportions existing according to the phase-rule method. It is assumed that the system can be considered to consist of three components, namely non-aromatics, aromatics and sulphur dioxide, respectively indicated by NA, A and SO_2 . The curve $e g f$ is the binode; e then represents the solubility of NA in SO_2 when the NA content is large, f the corresponding solubility of NA in SO_2 when the NA content is small. The area enclosed by the binode and the part $e f$ of the horizontal axis is the heterogeneous field in which dissociation takes place into two phases differing quantitatively in composition. The part $e g$ is the geometrical place of the phases rich in NA (raffinate layers), the part $f g$ that of the phases poor in NA (extract layers) in equilibrium with the first; g is the critical point at which the compositions of the two phases become quantitatively equal.

It has now been found that as the aromatic content of the raffinate layer decreases so the ratio of the aromatic content in the extract layer that in the raffinate layer, becomes smaller, in consequence of which the effect of the treatment by repeated extractions becomes unfavourable. With a high aromatic content this ratio exceeds unity; with a lower aromatic content it becomes less and may decrease to below unity.

From the position of the conjugational lines in the heterogeneous field it is immediately seen what the proportion is between the aromatic content of the extract and raffinate layers. With a positive gradient in respect to the horizontal axis the proportion is greater, with a negative gra-

dient it is smaller than unity. Experiments show that, as already stated above, the former is the case with a high aromatic content, e. g. with a mixture of NA and A of the composition r , and the latter with low aromatic content, e. g. with a mixture of NA and A of the composition h . On the mixture r being treated with SO_2 , given a fully balanced state of equilibrium, the phases t and u are formed with a ratio of the aromatic content of extract and raffinate layers equal to

$$\frac{u_e}{t_b} > 1,$$

whilst when the mixture h is treated with the same percentage of SO_2 , forming phases w and x , the ratio is

$$\frac{x_d}{w_a} < 1.$$

From this it is apparent that the greatest refining effect is obtained with a relatively high aromatic content as compared with that obtained with a low aromatic content, that is to say: the last remains of aromatics are removed more slowly.

The object of this invention is to provide means by which also with a low aromatic content a satisfactory refining effect is always obtained, i. e. by which the ratio of aromatic content in the extract layer to aromatic content in the raffinate layer is as large as possible.

This object can be obtained according to our invention by adding to the material to be treated—logically not before the aromatic content is reduced, for instance after primary extraction with liquid SO_2 alone—substances which bring about a favourable change in the said ratio.

As such may be considered, for instance, benzol and toluol, which increases the percentage of components soluble in SO_2 so as to attain the object described above.

An object of this invention is to effect the extraction with liquid sulphur dioxide in the presence of an auxiliary substance which increases the percentage of components soluble in liquid sulphur dioxide.

In order to facilitate control over the conditions then arising recourse is again had to the representation usual in the science of phases according to Fig. 2, in which benzol, indicated by B, occurs as the fourth component in the system.

Although the most obvious representation would be a tetrahedron with the four components in the corners, preference has been given to a partly rectangular form, which may be imagined

100 105 110

as being constructed from Fig. 1 by marking off the B content perpendicular to the drawing plane. A triangular prism is then obtained, of which the perpendicular through A represents mixtures containing only A and B. Thus any plane parallel to the base indicates a composition in which A and B occur in constant proportion. One may, therefore, speak of the 0%-B plane (the base shown in Fig. 1), the 50%-B plane (Fig. 2) and so on. With this method of representation the proportions between the other components, with varying composition of the total aromatics (i. e. the aromatics A originally existing plus the benzol B added), come better to the fore than in a tetrahedron.

In Fig. 2 the 50%-B plane is shown by way of example. The heterogeneous field is enclosed by the lines $e'f'$ and $f'g'e'$.

If in the 0%-B plane a raffinate layer t had been obtained (Fig. 1), then on SO_2 being added up to say y a raffinate layer w and an extract layer x would result with an unfavourable refining effect. If, however, a quantity of benzol is added equal to the quantity of aromatics already present (whereby one comes to the 50%-B plane), then a proportion of A+B concentrations in extract and raffinate layers (Fig. 2) is obtained, which is considerably more favourable

$$\left(\frac{zm}{pl} \right).$$

With an absolutely equal distribution of A and B in extract and raffinate layers this proportion would be just as favourable as with A alone; it is true that the distribution is not so favourable as this and in the extract layer with high benzol content there is relatively more B, but this difference is not such as to neutralize the favourable effect of the process described, and certainly not when the drawn-off extract layers contain little benzol. The treatment should, therefore, preferably be so conducted that when beginning with $NA+A$ and $B+SO_2$ one obtains $NA+B+little SO_2$ as raffinate and $SO_2+A+little benzol$ as extract. This is attained by making use of the counter-current method of extraction.

Example

50 Working on a Venezuelan spindle oil distillate with 28% A, and treating with 200% by weight SO_2 in counter-current, a raffinate with 4% A is obtained; yield 71%.

This raffinate treated with 200% SO_2 and 20% benzol (the quantities are calculated on the raffinate) produces a record raffinate with 2.5% A; yield 67% (calculated on distillate).

When this second raffinate is again treated with the same quantity of SO_2+B , without the old SO_2 and benzol first being evaporated, the third raffinate has 1% A; yield 63%.

If, however, the first raffinate mentioned above were again edeleanuized with only SO_2 , there would be produced by treating the first raffinate once with 200% SO_2 a raffinate with 3% A and yield 69%, whereas if the first raffinate had been treated twice with 200% SO_2 the result would have been a raffinate with 2.5% A and yield 68%. Even on further treatment with SO_2 only the percentage of A in the raffinate is reduced but very little, so that a raffinate with 1% A is hardly attainable.

It is obvious that instead of benzol another suitable substance having the favourable effect described above can be taken, the application of

which then likewise comes within the scope of the present invention.

Further the benzol or other agent used can be recovered from the raffinate and the extract layers, either separately or together with the SO_2 , in a known manner, for instance by distillation followed, if necessary, by fractionated condensation. If recovered together with the SO_2 , a reparation can be carried out to advantage in a known manner.

Having described our invention and illustrated the same, but without any intent to be limited thereby, what we claim is as follows:—

1. A process for the manufacture of refined transformer, spindle and lubricating oils from a mixture of heavy hydrocarbons containing aromatic hydrocarbons, comprising extracting said mixture with liquid sulphur dioxide in the presence of a fluid aromatic hydrocarbon having the character and action of benzol to increase the content of components soluble in liquid sulphur dioxide, whereby the percentage of initial materials soluble in liquid sulphur dioxide in said mixture of hydrocarbons is increased and a separation into an extract layer and a raffinate layer is obtained.

2. A process for the manufacture of refined transformer, spindle and lubricating oils from a mixture of heavy hydrocarbons containing aromatic hydrocarbons, comprising extracting said mixture with liquid sulphur dioxide in the presence of a fluid aromatic hydrocarbon having the character and action of benzol and separable from the raffinate layer by distillation, to increase the content of components soluble in liquid sulphur dioxide, whereby the percentage of initial materials soluble in liquid sulphur dioxide in said mixture of hydrocarbons is increased and a separation into an extract layer and a raffinate layer is obtained.

3. A process for the manufacture of refined transformer, spindle and lubricating oils from a mixture of heavy hydrocarbons containing aromatic hydrocarbons, by means of liquid sulphur dioxide, comprising adding to said mixture in addition to liquid sulphur dioxide a fluid aromatic hydrocarbon having the character and action of benzol and separable from the raffinate layer by distillation, to increase the content of components soluble in liquid sulphur dioxide, whereby the percentage of materials soluble in liquid sulphur dioxide in said mixture of hydrocarbons is increased, and allowing the mixture to separate into an extract layer and a raffinate layer.

4. In the process for the manufacture of refined transformer, spindle and lubricating oils from a mixture of heavy hydrocarbon containing aromatic hydrocarbons, by means of liquid sulphur dioxide, the step of adding to the liquid sulphur dioxide a fluid aromatic hydrocarbon having the character and action of benzol to increase the content of components soluble in liquid sulphur dioxide, by means of which the ratio of high boiling aromatic content in the extract layer to high boiling aromatic content in the raffinate layer is increased.

5. A process for refining petroleum lubricating oil fractions containing undesired aromatics, comprising extracting the fraction with liquid sulphur dioxide in the presence of a fluid aromatic hydrocarbon having the character and action of benzol to increase the content of components soluble in liquid sulphur dioxide and further characterized by being substantially free from the non-benzenoid constituents of extracts and by the

- ing separable from the fraction by distillation, the presence of said added aromatic hydrocarbon causing an increased extraction of the undesired aromatics initially in said fraction.
- 5 6. A process for refining petroleum lubricating oil fractions containing substantial percentages of undesired aromatics, comprising extracting the fraction with liquid sulphur dioxide alone to produce a raffinate containing a small amount of aromatics; then further reducing the content of initial aromatics by extracting said raffinate with liquid sulphur dioxide in the presence of a fluid aromatic hydrocarbon having the character and action of benzol to increase the content of components soluble in liquid sulphur dioxide and also characterized by being substantially free from the non-benzenoid constituents of extracts and by being separable from the fraction by distillation.
- 10 7. A process for the manufacture of refined transformer, spindle and lubricating oils from a mixture of hydrocarbons containing aromatic hydrocarbons, comprising extracting the mixture with liquid sulphur dioxide alone to produce a raffinate containing a small amount of aromatics; then further reducing the content of initial aromatics by extracting said raffinate with liquid sulphur dioxide in the presence of a fluid aromatic hydrocarbon having the character and action of benzol to increase the content of components soluble in liquid sulphur dioxide, whereby the percentage of initial materials soluble in liquid sulphur dioxide in said raffinate is increased and a separation into a second extract and raffinate layer is obtained.
- 15 8. A process for the manufacture of refined transformer, spindle and lubricating oils from a mixture of hydrocarbons containing aromatic hydrocarbons, comprising extracting the mixture with liquid sulphur dioxide alone to produce a raffinate containing a small amount of aromatics; then further reducing the content of initial aromatics by extracting said raffinate with liquid sulphur dioxide in the presence of a fluid aromatic hydrocarbon having the character and action of benzol and separable from the raffinate layer by distillation, to increase the content of components soluble in liquid sulphur dioxide, whereby the percentage of materials soluble in liquid sulphur dioxide in said raffinate is increased and a separation into a second extract and raffinate layer is obtained.
- 20 9. A process for the manufacture of refined transformer, spindle and lubricating oils from a mixture of hydrocarbons containing aromatic hydrocarbons, comprising extracting the mixture with liquid sulphur dioxide plus a fluid aromatic hydrocarbon having the character and action of benzol to increase the content of components soluble in liquid sulphur dioxide, the presence of said aromatic hydrocarbon causing an increased extraction of the aromatics initially in said mixture of hydrocarbons.
- 25 10. A process for the manufacture of refined transformer, spindle and lubricating oils from a mixture of hydrocarbons containing aromatic hydrocarbons, comprising extracting the mixture with liquid sulphur dioxide plus a fluid aromatic hydrocarbon having the character and action of benzol to increase the content of components soluble in liquid sulphur dioxide, the presence of said aromatic hydrocarbon causing an increased extraction of the aromatics initially in said mixture of hydrocarbons.
- 30 11. A process for the manufacture of refined transformer, spindle and lubricating oils from a mixture of hydrocarbons containing aromatic hydrocarbons, comprising extracting the mixture with liquid sulphur dioxide plus a fluid aromatic hydrocarbon having the character and action of benzol to increase the content of components soluble in liquid sulphur dioxide, the presence of said aromatic hydrocarbon causing an increased extraction of the aromatics initially in said mixture of hydrocarbons.
- 35 12. A process for the manufacture of refined transformer, spindle and lubricating oils from a mixture of hydrocarbons containing aromatic hydrocarbons, comprising extracting the mixture with liquid sulphur dioxide plus a fluid aromatic hydrocarbon having the character and action of benzol to increase the content of components soluble in liquid sulphur dioxide, the presence of said aromatic hydrocarbon causing an increased extraction of the aromatics initially in said mixture of hydrocarbons.
- 40 13. A process for refining petroleum lubricating oil fractions containing undesired aromatics, comprising extracting the fraction with liquid sulphur dioxide plus a fluid aromatic hydrocarbon having the character and action of benzol to increase the content of components soluble in liquid sulphur dioxide and further characterized by being substantially free from the non-benzenoid constituents of extracts and by being separable from the fraction by distillation, the presence of said aromatic hydrocarbon causing an increased extraction of the undesired aromatics initially in said fraction.
- 45 14. A process for refining petroleum lubricating oil fractions containing substantial percentages of undesired aromatics, comprising extracting the fraction with liquid sulphur dioxide alone to produce a raffinate containing a small amount of aromatics, then further reducing the content of initial aromatics by extracting said raffinate with liquid sulphur dioxide plus a fluid aromatic hydrocarbon having the character and action of benzol to increase the content of components soluble in liquid sulphur dioxide and further characterized by being substantially free from the non-benzenoid constituents of extracts and by being separable from the raffinate by distillation, the presence of said aromatic hydrocarbon causing an increased extraction of the undesired aromatics initially in said raffinate.
- 50 15. A process for the manufacture of refined transformer, spindle and lubricating oils from a mixture of heavy hydrocarbons containing aromatic hydrocarbons, comprising extracting the mixture with liquid sulphur dioxide in the presence of benzol, whereby the percentage of materials soluble in liquid sulphur dioxide in said mixture of hydrocarbons is increased and a separation into an extract layer and a raffinate layer is obtained.
- 55 16. In the process for the manufacture of refined transformer, spindle and lubricating oils from a mixture of heavy hydrocarbons containing aromatic hydrocarbons, by means of liquid sulphur dioxide, the step of adding benzol to the liquid sulphur dioxide, by means of which the ratio of high boiling aromatic content in the extract
- 60 65 70 75 80 85 90 95 100 105 110 115 120 125 130 135 140 145 150

- layer to high boiling aromatic content in the raffinate layer is increased.
17. A process for the manufacture of refined transformer, spindle and lubricating oils from a mixture of heavy hydrocarbons containing aromatic hydrocarbons comprising adding benzol to said mixture whereby the percentage of total aromatic hydrocarbons in the extract and raffinate layers is increased and adding liquid sulphur dioxide to said mixture to separate the hydrocarbons into an extract layer and a raffinate layer.
18. A process for refining petroleum lubricating oil fractions containing undesired aromatics, comprising extracting the fraction with liquid sulphur dioxide in the presence of benzol substantially free from the non-benzenoid constituents of extracts, the presence of said benzol causing an increased extraction of the undesired aromatics initially in said fraction.
19. A process for the manufacture of refined transformer, spindle and lubricating oils from a mixture of heavy hydrocarbons containing aromatic hydrocarbons, comprising extracting said mixture with liquid sulphur dioxide plus benzol.
20. A process for refining petroleum lubricating oil fractions containing undesired aromatic hydrocarbons comprising extracting the fraction by the counter-current method with liquid sulphur dioxide plus benzol, the presence of said benzol causing an increased extraction of the undesired aromatics initially in said fraction.
21. A process for refining petroleum lubricating oil fractions containing undesired aromatics, comprising extracting the fraction with liquid sulphur dioxide plus benzol substantially free from the non-benzenoid constituents of extracts.
22. A process for the manufacture of refined transformer, spindle and lubricating oils from a mixture of heavy hydrocarbons containing aromatic hydrocarbons comprising extracting said mixture with liquid sulphur dioxide alone, separating the extract layer from the raffinate layer and extracting said raffinate layer with liquid sulphur dioxide plus benzol, the presence of said benzol causing an increased percentage of initial materials in the mixture of hydrocarbon oils in said raffinate layer to be soluble in said liquid sulphur dioxide.
23. A process for refining petroleum lubricating oil fractions containing substantial percentages of undesired aromatic hydrocarbons, comprising extracting the fraction with liquid sulphur dioxide alone to produce a raffinate containing a small amount of aromatics, then further reducing the content of initial aromatics by extracting said raffinate by the counter-current method with liquid sulphur dioxide plus benzol, the presence of said benzol causing an increased extraction of the undesired aromatics initially in said raffinate.
24. A process for refining petroleum lubricating oil fractions containing substantial percent-
- ages of undesired aromatics, comprising extracting the fraction with liquid sulphur dioxide alone to produce a raffinate containing a small amount of aromatics, then further reducing the content of initial aromatics by extracting said raffinate with liquid sulphur dioxide plus benzol substantially free from the non-benzenoid constituents of extracts.
25. A process for refining petroleum lubricating oil fractions containing large amounts of aromatics which it is desired to remove, comprising extracting the fraction at least once with liquid sulphur dioxide alone in order to produce a raffinate containing a small amount of aromatics, then further extracting said raffinate with liquid sulphur dioxide plus benzol, this latter extraction being repeated until the amount of initial aromatics contained in the final raffinate is less than would result from repeated extraction of the original fraction with pure liquid sulphur dioxide alone.
26. A process for refining petroleum lubricating oil fractions containing undesired aromatic hydrocarbons, comprising extracting the fraction by the counter-current method with liquid sulphur dioxide plus about an equal amount of benzol.
27. A process for refining petroleum lubricating oil fractions containing substantial percentages of undesired aromatic hydrocarbons, comprising extracting the fraction with liquid sulphur dioxide to produce a raffinate containing a small amount of aromatics, then further reducing the content of aromatics by extracting said raffinate by the counter-current method with liquid sulphur dioxide plus about an equal amount of benzol.
28. A process for refining petroleum lubricating oil fractions containing aromatics which it is desired to remove, comprising extracting the fraction in the counter-current manner with about 200% by weight of liquid sulphur dioxide alone, then extracting the raffinate in the counter-current manner with about 200% by weight of liquid sulphur dioxide plus about 20% by weight of benzol, and removing from the final raffinate any sulphur dioxide and benzol contained therein.
29. A process for refining petroleum lubricating oil fractions containing aromatics which it is desired to remove, comprising extracting the fraction in the counter-current manner with about 200% by weight of liquid sulphur dioxide plus about 20% by weight of benzol, then extracting the second raffinate with a like amount of liquid sulphur dioxide plus a like amount of benzol, and removing from the final raffinate any sulphur dioxide and benzol contained therein.
